UNITED STATES PATENT OFFICE

166,083

TAPE-DISPENSING MACHINE

Alfred P. Krueger, Stratford, Conn., assignor to
Derby Sealers, Incorporated, Derby, Conn., a
corporation of Connecticut

Application April 28, 1951, Serial No. 15,001

Term of patent 14 years

(Cl. D74—1)

To all whom it may concern:

Be it known that I, Alfred P. Krueger, a citizen of the United States, residing in Stratford, in the county of Fairfield and State of Connecticut, have invented a new, original, and ornamental Design for a Tape-Dispensing Machine, of which the following is a specification, reference being had to the accompanying drawings, forming part thereof, in which:

Fig. 1 is a side elevational view of a tape-dispensing machine embodying my new design;

Fig. 2 is a front elevational view thereof;

Fig. 3 is a top plan view; and

Fig. 4 is a side elevational view showing the side opposite that shown in Fig. 1.

The representation of a roll of tape shown in

broken lines in Fig. 1 has been omitted from the other figures for convenience of illustration.

I claim:

The ornamental design for a tape-dispensing machine, substantially as shown and described.

ALFRED P. KRUEGER.
